UNITED STATES PATENT OFFICE.

ROY G. SANDS, OF CHICAGO, ILLINOIS, ASSIGNOR TO COOK ELECTRIC COMPANY,
OF CHICAGO, ILLINOIS, A CORPORATION OF ILLINOIS.

RENEWABLE ELECTRIC FUSE.

Application filed November 22, 1920. Serial No. 425,648.

To all whom it may concern:

Be it known that I, ROY G. SANDS, a citizen of the United States, residing at Chicago, in the county of Cook and State of Illinois, have invented new and useful Improvements in Renewable Electric Fuses, of which the following is a full, clear, concise, and exact description, reference being had to the accompanying drawing, forming a part of this specification.

My invention relates to electric fuses and it has special reference to fuses that are known as enclosed renewable fuses.

More particularly my invention relates to an improved electric fuse in which the chamber containing the fusible element communicates with the outer air through a restricted passageway comprised in a washer and of such form that the gases generated by the vaporization of the fusible element are properly vented from this chamber, but the flame thus occasioned is precluded from extending exteriorly of the fuse by reason of said venting passageway. To meet the Fire Underwriters' specifications, an enclosed renewable fuse must wholly confine the flame at the time of the vaporization of the fusible element to the interior of the fuse so that by no possibility may fire be projected exteriorly of the fuse.

An object, therefore, of my invention is to provide a fireproof enclosed renewable fuse which comprises elements that may be recurrently used with the exception of the fusible element.

Another object of my invention is to provide a fuse of the character indicated above in which the passageways serving to vent the fuse for expelling the gases from the interior thereof may be maintained permanently open and substantially free from clogging deposits which tend to form from the vapors generated at the time of the exploding of the fusible element.

A further object of my invention is to provide a fuse as described above in which a venting tortuous passage-way is formed in a washer of a unitary structure that permits of the gases being vented through the washers without the possibility of any flame being projected exteriorly of the fuse. The unitary structure of my washer allows of the ready assembling of the fuse and the expeditious renewing of the fusible element

after exploding. As a result of the use of the venting washer of my present invention, no danger or likelihood exists of the fuse being wrongly assembled whereby the venting passage-way may be permanently closed.

For a better understanding of the nature and the scope of my invention reference may be had to the following description and the accompanying drawing, in which—

Fig. 1 is a view, partially in elevation and partially in section, of an enclosed renewable fuse constructed in accordance with my invention;

Fig. 2 is a disassembled view showing in detail portions of the several elements comprising the fuse of Fig. 1;

Fig. 3 is a cross sectional view of a portion of a fuse comprising a knife-blade terminal and embodying a form of my invention, and

Fig. 4 is a modified form of a fuse having a removable washer of the general character illustrated in Figs. 1 and 2 but in which the removable cap is not secured thereto by means of a screw, as is shown in the structures of Figs. 1 and 2.

Referring to Figs. 1 and 2, a fusible element 1 of a usual form is contained within an insulating shell 2 that serves as the casing of the fuse. The fusible element 1 is slotted at its ends 4, as shown at 3, the ends 4 being bent at right angles and, in the assembled structure, being interposed between the upper face of a washer 5 and the inner face of an end cap 14.

The washer 5 is a built-up unitary structure comprising an exterior shell member 6, a core 7 and a face plate 8. The shell member 6 is provided adjacent to its upper end with a series of circumferentially arranged and spaced openings 9. The lower end of the shell 6 is provided with an opening, as shown in Fig. 1, through which a shank portion 10 of the core 7 may project. In assembling the washer, the core 7 is extended through the opening in the face plate 8 which is beveled, as shown. The upper edge of the core is then swaged to make a tight fit between the core 7 and the face plate 8. The shank 10 is then projected through the opening formed in the shell 6 and is peened to firmly hold the core 7 in fixed position. The core 7 is provided with a longitudinally extending opening 11 that is in-

teriorly threaded at its lower portion. A narrower longitudinally extending opening 12 extends from the opening 11 to a transverse bore 13 that is formed adjacent to the shank portion 10. In this manner the transverse bore 13 communicates with the opening 11 through the restricted passageway 12. The built-up washer 5 is, in this manner, assembled into a unitary structure of permanent form.

A series of tortuous passageways for venting the interior of the fuse through the openings 9, 12 and 13 is formed in the washer by the reason of the annular space 11^a between the exterior of the core 7 and the interior of the enveloping shell 6.

An end cap 14 is interiorly threaded to engage the exteriorly threaded end of the insulating shell 2. At its center portion, the cap 14 is counter sunk and provided with a central opening 15 through which the shank of a holding screw 16 may freely pass. The end of the shank is threaded to engage the thread formed in the core 7 at the lower end of the opening 11. The head of the screw 16 is received in the counter-sunk portion of the cap 14. The screw 16 is provided with a longitudinally extending opening 17 that may be of the same bore as the opening 12. The opening 17 also registers with the opening 12 thereby forming a restricted passageway to the exterior of the fuse. The screw 16 serves to firmly retain the end 4 of the fusible element in close contact between the cap 14 and the washer 5. The exposed face of the head of the screw 16 is transversely slotted at 16^a whereby the screw may be conveniently engaged with a proper instrument when it is desired to replace the fusible element 1.

When the fusible element 1 is vaporized, the gases resulting therefrom and contained within the fuse chamber of the shell 2, are vented through the restricted and tortuous passageways which open into the fuse chamber through the openings 9 formed in the shell 6 of the washer 5. The openings 9 severally communicate through the annular space 11^a, the transverse bore 13 and the opening 12 with the opening 17 formed in the screw 16, which opening directly communicates with the outer air.

It has been found that the deposits resulting from the gases occasioned by the vaporization of the fusible element do not substantially clog the venting passageways mentioned above. As a consequence thereof, my present fuse may be repeatedly renewed and used without having its venting properties impaired while, at the same time, fire and flame resulting from the vaporization of the fusible element are precluded from following the gases and extending exteriorly of the fuse. Furthermore if at any time the passages should become deformed or ob-

structed in any way by portions of the melted fuse, the washer may be replaced as a unit, the tortuous passageway being through and within the washer and independent of the shell structure.

In Fig. 3, an end cap 14^a cooperates with a terminal member 18 that is provided with a knife-blade extension 19. The member 18 is retained in position by the threaded engagement of the cap 14^a with the shell 2. A screw 16^a is, in this instance, offset from the center line of the fuse but the unitary washer 5^a is generally of the same construction as the washer of Figs. 1 and 2 except for the obvious modifications necessitated by the offsetting of the screw 16^a. The venting in this fuse is likewise accomplished through the openings 9^a formed in the enveloping shell member 6^a of the washer.

The casing 2 of the fuse illustrated in Fig. 4 is provided at its end with a metallic ferrule 19 which is a common form of construction. The core member 7^b of the unitary washer 5^b is provided with a longitudinally extending opening 12^b of uniform bore and is enclosed in a shell 6^b. The opening 12^b registers with the opening 13 formed in the bent-over end 4 of the fusible element 1 and a correspondingly located opening 21 formed in the end cap 14^b. The exterior of the core 7^b is provided with a series of annular projecting fins 22 whereby the gases emanating from the shell 2 may be quickly cooled before entering into the opening 12^b which is in direct communication with the outer air. The bent-over end 4 of the fusible element 1 is firmly held intermediate the cap 14^b and the washer 5^b without the need of a retaining screw, such as the screw 16 of Figs. 1 and 3.

While I have described in detail several embodiments of my invention it is to be understood that I desire only such limitations to be imposed thereupon as are dictated by the prior art and specifically set forth in the claims forming a part of this specification.

Having thus described my invention what I now claim as new and desire to secure by Letters Patent is:

1. An enclosed electric fuse comprising a washer of unitary structure having a defined tortuous passageway formed therethrough for restricting the venting of the associated electric fuse.
2. An enclosed electric fuse comprising a shell member, a renewable fusible element, a removable washer engaging said shell member and fusible element, and a cap member engaging the end of said shell member, said washer being of unitary structure and having a tortuous and restricted passageway formed therethrough for venting said fuse.
3. An enclosed electric fuse comprising a

shell member, a renewable fusible element, a removable washer, and a cap member, said washer being a unitary structure and having a defined tortuous passageway formed therethrough through which communication is afforded between the outer air and the interior of the fuse.

4. An enclosed electric fuse comprising a shell member, a removable washer of unitary structure, and an end cap, said fuse being vented through a tortuous passageway formed within said washer.

5. An enclosed electric fuse comprising a shell member, a renewable fusible element, a removable washer and a terminal member, said washer being a unitary structure and having a tortuous path formed therethrough which communicates with openings formed in said fusible element and said terminal member.

6. A washer for a renewable electric fuse comprising an outer shell member, and an inner core member enveloped thereby but spaced to form an annular passageway, each 25 of said members having openings formed therein which, in the aggregate, constitutes a restricted tortuous path comprising said annular space.

7. A washer for an enclosed fuse comprising a shell member, a core member spaced therefrom to form an annular passageway, and a face plate, said shell member having an opening formed therein to communicate with said annular passageway and said core member having an opening that likewise communicates with said annular passageway and the outer air.

8. A built-up washer for an enclosed fuse comprising an exterior shell member and a core member contained therein but spaced therefrom to form an annular space, said shell member having an opening formed therein which communicates with said annular space at the opposite end of said shell member, the opening formed in said core member affording communication with the outer air.

9. An enclosed renewable electric fuse comprising a shell member, end caps therefor, a renewable fusible element of greater length than and extending through said shell member, and removable washers at the ends of the shell member, said washers abutting said end caps and the ends of said fusible element overlapping the exposed faces of the washers and having contact with the inner faces of the end caps when the latter are in position, and said washers being unitary structures having tortuous venting paths formed therethrough for venting the fuse.

10. An enclosed renewable electric fuse comprising a shell member and end caps therefor, a renewable fusible element of

greater length than and extending through 65 said shell member, and removable washers at the ends of the shell member, said washers abutting said end caps and the ends of the fusible element overlapping the exposed faces of the washers and having contact 70 with the inner faces of the end caps when in position, and said washers having tortuous passage-ways formed therethrough through which communication is afforded for the fuse with the outer air.

11. An enclosed electric fuse comprising a shell member, end caps therefor, a renewable fusible element of greater length than and extending through said shell member, and a washer at one end of the shell member which is held in abutting relation to the corresponding end cap, an end of the fusible element overlapping the outer face of said washer and being held in position therebetween and the inner face of the abutting 85 end cap when the latter is in position, and said washer having a tortuous path formed therethrough through which the fuse may be vented and forming a supporting means for the fusible element whereby said fusible element may be positioned prior to the placing 90 of the end cap in position.

12. An enclosed electric fuse comprising a shell member, end caps therefor, a renewable fusible element of greater length than 95 and extending through said shell member, and a washer at one end of the shell member which is held in abutting relation to the corresponding end cap, an end of the fusible element overlapping the outer face of 100 said washer and being held in position therebetween and the inner face of the abutting end cap when the latter is in position, and said washer being a unitary structure within which a tortuous venting path for the 105 fuse is formed and serving as a supporting means for the fusible element whereby the fusible element may be positioned prior to the placing of the end cap in position.

13. An enclosed electric fuse comprising 110 a shell member, removable washers fitted against the ends of the shell member, a fusible element extending through the shell member and having its ends bent over and in engagement with the outer faces of the 115 washers, and end caps for the shell member which when in position serve to hold the ends of said fusible element in contact with the washers, each of said washers having a tortuous passage therethrough for venting 120 the fuse.

14. An enclosed electric fuse comprising a shell member, removable washers fitted against the ends of the shell member, a fusible element extending through the shell member and having its ends bent over and in engagement with the outer faces of the 125 washers and end caps for the shell member

which when in position serve to hold the ends of said fusible element in contact with the washers, each of said washers being removable and having a unitary structure within which a tortuous venting path is formed that affords restricted communication for the fuse with the outer air.

In witness whereof I have hereunto subscribed my name.
